ARGENTINA

SPITTOON

Application filed December 23, 1929, Serial No. 416,078, and in Argentina October 28, 1929.

The present invention concerns a spittoon especially intended for being placed in establishments, theatres, public rooms, streets, walks, etc., which comprises a reservoir for a disinfecting solution kept at a certain level and which communicates with a receptacle or spit-box through a tube intercepted by a rotary valve and by means of which disposition said solution is kept at a constant level.

10 By the adoption of this spittoon an important problem is resolved in the good of public health, because there is no doubt that the passers-by or the attenders to said places will spit into the spittoons instead of upon 15 the ground as is now the case where such utensils are not found, particularly in streets and walks.

The receptacle or spittoon is placed into a box which is open at its upper part and from 20 which it can be recharged quite easily, for which operation, to avoid slabbering, the valve which intercepts the communication between the spit-box and the reservoir for the disinfecting solution, absolutely must be 25 closed.

One or more of the faces of the reservoir may be protected, or not, by glass and, at all 30 events, provided with guides for placing upon them painted plates or casts which may constitute advertisements for general publicity or theatre programmes or indications of public utility.

For the better understanding of this description, reference is made to the accompanying detailed drawings in which:

Figure 1 is a perspective view of a publicity spittoon constructed in accordance with our invention.

Figure 2 is a longitudinal section of the receptacle which constitutes the spittoon.

Figure 3 is a detail of the intercepting valve, the movable member of which, when raised, closes the communication between the reservoir and the spit-box.

In the drawings 1 is the column which supports the reservoir of the disinfecting solution 2, one or more of its fronts carrying glasses or crystals 3 in combination with slots 4 which allow the introduction and replac-

ing of boards 5 carrying advertisements or indications of public utility.

The reservoir 2 is connected with the receptacle 9 by means of a tube or conduit 6 which is provided at its lower end with a 55 rotary cylindrical valve 7 for opening and closing the conduit. Said valve carries a nozzle 8 which is adapted to communicate, through the valve, with the conduit 6 when the nozzle is in the position shown in full 60 lines. In this position of the nozzle the disinfectant liquid when it reaches a predetermined level will close the discharge orifice of the nozzle and stop the flow of liquid from the reservoir. However, at the moment at which the level of the liquid in the receptacle 9 tends to descend uncovering the outlet orifice of the 65 nozzle the flow of liquid is produced until the normal level is again reached.

The receptacle 9 is put into the outer case 70 from which it cannot be extracted without opening the raising door 11, and lifting the nozzle 8, to rotate the valve thus closing the communication between the reservoir and receptacle.

75 Into the interior of the spit-box has been placed an unmountable grid of sharp-edged bars 12, with the object of hiding to the eye the presence of the spittles accumulated in it.

As will be understood, the capacity or dimensions of the reservoir 2, as well as those of the spit-box and the general ornamentation of the whole can vary without altering the validity of the invention.

80 The boards 5 can also be fixed behind the glasses or crystals 3, mounting these into hinged doors provided with locks or, at all events, any kind of lock, padlock or the like can be provided to prevent the unauthorized removal of advertisements or inscriptions.

85 It also remains understood that, to increase the public utility of the publicity spittoon, measuring instruments such as clocks, barometers, thermometers or hydrometers and the like can be added.

Claims:

1. A spittoon comprising a receptacle, a reservoir mounted above the latter, a conduit connecting the reservoir and receptacle, and a nozzle rotatably connected with the conduit 100

and operable to retain the receptacle in operative relation to the conduit.

5   2. A spittoon comprising a case, a column mounted thereon, a reservoir mounted on the column, a receptacle removably mounted in the case, a conduit in the column connecting the reservoir and receptacle, a cylindrical rotary valve in the lower end of the conduit for opening and closing the latter, and a nozzle communicating with said valve and adapted to project into the receptacle when the valve is in position for opening the conduit, said nozzle constituting means to prevent withdrawal of the receptacle from said case.

10   15   CARLOS OCCHIPINTI.
                  GASPAR OCCHIPINTI.
                  CRISPIN GONZALEZ.
